UNITED STATES PATENT OFFICE.

MAX KAW, OF CINCINNATI, OHIO, ASSIGNOR TO THE L. SCHREIBER & SONS COMPANY, OF CINCINNATI, OHIO, A CORPORATION.

ELEVATOR-GATE.

SPECIFICATION forming part of Letters Patent No. 764,130, dated July 5, 1904.

Application filed March 21, 1904. Serial No. 199,310. (No model.)

To all whom it may concern:

Be it known that I, MAX KAW, a citizen of the United States, residing at Cincinnati, in the county of Hamilton and State of Ohio, have invented certain new and useful Improvements in Elevator-Gates, of which the following is a specification:

My invention relates to an improvement in an elevator-door opening and closing mechanism.

My invention relates to the type employing two or more moving panels sliding in parallel planes which unfold into closing position across the door-opening and which fold up into door-opening position behind a stationary panel equal substantially to the width of one of the moving panels.

The features of my invention are more fully set forth in the description of the accompanying drawings, forming a part of this specification, in which—

Figure 1 is an inside elevation of my improvement as applied to two moving door members and shown in their closed position. Fig. 2 illustrates the same in their open position. Fig. 3 is a top plan view of the actuating mechanism. Fig. 4 is a top plan view of my improvement for three door members. Fig. 5 is a plan view of a modified form of lever.

A represents the doorway-frame.

B B' represent horizontal top guideways, from which are suspended by brackets a and rollers b the door-panels C D in parallel planes.

C is the slower moving member, and D is the faster moving member.

E represents the stationary panel, behind which the panels C D fold.

F represents a bracket secured to the edge of the frame A opposite the inner edge of the panel E. This bracket is provided with a bracket-ear e.

d represents a journal-bolt in the ear e.

Each panel is provided with two lever members hinged together to the stationary abutment and to the said panel. Thus panel D has the lever members G H pivoted together and hinged to the bolt d of the bracket F and

to the bolt g or the ears of the bracket h, attached to the inner edge of panel D. Preferably member H has the inwardly-extended finger m overlapping the coöperating lever G and serving to limit the movement of the levers G H to a position at one side of the dead-center. Similarly, panel C has the two lever members J K pivoted together and hinged to the bolt d of bracket F and to the bolt i of bracket h, attached to the inner edge of the panel C. Similarly, if a third panel were employed it would be provided with the two lever members L M, as shown in Fig. 4, all three of the inner members being hinged to abutment F'. These levers operate in the respective planes of their respective panels. The inner members J, G, and L are of different length, thereby imparting simultaneously different lengths of travel to their respective panels. The inner members G and J (the members which are hinged to the stationary abutment) are connected together by the bolt n. I preferably employ the connecting-bolts n' and n'' (see Fig. 4) when three panels are employed. The two lever members which are hinged to the stationary abutment are of different length and joined so as to move as a single element.

It is evident that I can employ as many moving door-panels as desired.

This is a very simple mechanism for the purpose described, and it is the only one of its lever class permitting of the unlimited extension of the moving panels. These levers are mounted to operate between the stationary abutment and the ends of the door-panels in the respective vertical planes of movement of the said panels. Thus they are out of the way and conveniently and effectively disposed.

In the modification shown in Fig. 5, O is a lever member which is hinged to the stationary abutment. This member is provided with the arms P Q in the parallel planes of the two panels. The two link-levers R S are hinged to the arms P Q and to their respective panels. This construction is an equivalent of the device shown in Fig. 3. The arms J G are rigidly secured together and move on a common center.

In the modification shown in Fig. 5 the arm P is connected to the arm Q integrally. While the method of uniting the arms is mechanically different, they are practically the same 5 in principle and mode of operation, being simply a choice of mechanical means or convenience of construction.

Having described my invention, I claim—

1. In an elevator-door opening and closing 10 device, a plurality of panels slideable in parallel planes, each panel having two lever members hinged together, to said panel and to a stationary abutment, and means connecting the lever members of the different panels 15 whereby they are operated in unison, substantially as described.
2. In an elevator-door opening and closing device, a plurality of panels slideable in parallel planes, each panel having two lever members extending from the panel in closed position to the adjacent stationary abutment, said two lever members being hinged together, to said panel and to said abutment, and means connecting the lever members of the different 20 panels, whereby they are actuated in unison, substantially as described.
3. In an elevator-door opening and closing device, a plurality of panels slideable in parallel planes, each panel having two lever members operating in the plane of sliding of its panel, said two lever members being hinged together, to said panel and to an adjacent stationary abutment and means connecting together the lever members which are hinged to said stationary abutment, substantially as described.
4. In an elevator-door opening and closing mechanism, a plurality of panels slideable in parallel planes, each panel having two lever members hinged together, to a stationary abutment and to the inner edge of said panel and means connecting those lever members which are hinged to the stationary abutment, substantially as described.
- 45 5. In an elevator-door opening and closing mechanism, a plurality of panels slideable in

parallel planes, each panel having two lever members hinged together, to said panel and to the adjacent stationary abutment, means connecting together those lever members 50 which are hinged to the stationary abutment, one of the lever members of the system having an overlapping finger adapted to engage over its coöperating lever member to limit the unfolding movements of the levers to a position at one side of the dead-center of the joints, substantially as described.

6. In an elevator-door opening and closing device, a plurality of panels slideable in parallel planes, each panel having two lever members hinged together, to said panel and to a stationary abutment, the lever members which are hinged to said abutment, being secured together and being of different lengths whereby they impart simultaneously different lengths 60 of travel to their respective panels, substantially as described.

7. In an elevator-door opening and closing device, a plurality of panels slideable in parallel planes, a journal-bracket attached to the 70 stationary abutment at one side, a journal-bracket attached to the edge of each panel, two lever members for each panel hinged together, to the journal-bracket on the abutment, and to the journal-bracket on the panel, 75 and means connecting together the lever members hinged to the stationary abutment, substantially as described.

8. In an elevator-door opening and closing device, a plurality of panels slideable in parallel planes, two lever members of different length, joined to act as a unit, hinged to a stationary abutment, and means connecting the said two levers with the said two panels, substantially as described.

In testimony whereof I have hereunto set my hand.

MAX KAW.
